UNITED STATES PATENT OFFICE.

LEO D. JONES, OF PHILADELPHIA, PENNSYLVANIA, ASSIGNOR TO THE SHARPLES SPECIALTY COMPANY, OF PHILADELPHIA, PENNSYLVANIA, A CORPORATION OF DELAWARE.

CENTRIFUGAL MACHINE.

Application filed April 9, 1926. Serial No. 100,796.

This invention relates to centrifugal machines and more especially to machines for concentrating the dispersed phase of an emulsion or suspension and separating the concentrated emulsion from the pure continuous phase.

In devices of this character the emulsion or suspension is fed into a centrifugal bowl and as it passes along the bowl the dispersed phase is gradually concentrated by centrifugal action either near the axis or the periphery of the bowl, depending upon the character of the emulsion or suspension. The concentrated emulsion and the pure continuous phase are discharged from the bowl through passageways leading from the bowl at different radial distances from its axis. Each discharge is controlled by a weir which may constitute a portion of the surface of the passageway or may comprise a separate member associated with the discharge passageway. The concentration of the emulsion depends upon the ratio of the rate of discharge of the concentrated emulsion to the rate of discharge of the continuous phase. Machines of this type now in use have the disadvantage that any decrease in capacity below the normal capacity of the machine results in a decrease in the ratio of the rate of discharge of the concentrated emulsion to the rate of discharge of the continuous phase thereby increasing the concentration of the emulsion. If the capacity at which the machine is operating is sufficiently reduced the emulsion may become sufficiently concentrated to produce coagulation or coggage of the discharge. Moreover, this type of machine has the additional disadvantage that any variation in the speed of rotation of the bowl produces a variation in the percentage concentration of the emulsion.

An object of this invention is a centrifugal machine for concentrating emulsions in which the concentration of the emulsion remains constant at different capacities or speeds of the machine.

One way of attaining this object is to control the concentrated emulsion discharge and the continuous phase discharge by weirs so designed that the ratio of the rate of discharge of concentrated emulsion to the rate of discharge of the pure continuous phase is sub-

stantially uniform at different capacities or speeds. The ratios of the discharges is maintained uniform by forming the weirs so that their edges lie along arcs of equal diameter circles having their centers coincident with the axis of the bowl. The ratio between the rates of discharges may be determined by the width of the weirs. With such an arrangement, the thickness of the discharge crests is substantially the same for both weirs at any given capacity or speed of the machine, and the volumes of the discharges bear the same relation to each other as do the width of the weirs controlling them. The widths of the weirs are so chosen that the desired concentration of the emulsion is obtained, and if it is desired to vary the concentration of the emulsion, the ratio of the weir widths is changed.

This invention is of particular utility in cream separators. With machines of the type heretofore on the market, it is necessary to operate each machine at a definite and predetermined capacity and speed in order to obtain a certain percentage of butter fat in the cream. A decrease in capacity results in an increase in the percentage of butter fat in the cream, and if the capacity is decreased sufficiently, cream ceases to flow entirely. Also a variation in the speed of operation of the machine results in a variation in the percentage of butter fat in the cream. A cream separator embodying this invention, however, discharges cream having a uniform percentage of butter fat at different capacities and speeds of the machine.

Other objects, novel features and advantages of this invention will be apparent from the following specification and accompanying drawings, wherein

Figure 1 illustrates in vertical section partly broken away a centrifugal machine bowl designed to discharge concentrated emulsion of uniform percentage at all capacities;

Figs. 2 and 3 are plan views of the weirs for controlling the discharges;

Fig. 4 illustrates diagrammatically the principle of the invention;

Fig. 5 is a vertical section partly broken away of a cream separator embodying the invention;

Fig. 6 is a similar enlarged view of the head of the bowl of the separator shown in Fig. 5; Fig. 7 is a section on the line 7—7 of Fig. 6; Fig. 8 is an enlarged sectional fragmentary

5 view of a modified head; and

Fig. 9 is a section on the line 9—9 of Fig. 8.

Referring now to Figs. 1 to 3 inclusive, 10 designates a centrifugal machine bowl having a head 11 which may be suitably connected to a spindle. The lower portion of the bowl is provided with a tubular projection 12 through which an emulsion or suspension may be introduced from a nozzle 12' and which may fit into a suitable guide bushing.

15 In the head 11 are provided two outlet passageways 13 and 14 of which 13 leads from a point nearer the axis of the bowl than does 14 and terminates at a point below the termination of 14. An annular disk 15 is screwed 20 into the lower face of the head 11 and surrounds one end of the outlet 13. Between the disk 15 and the inner surface of the bowl is arranged a plurality of wings 15^a, three being preferred, to cause the liquid in the 25 annular space between the disk and the bowl to rotate at the same speed as the bowl. One or more portions of the disk are cut away to provide one or more weirs 16, the edge or edges of which lie on the circumference of a circle concentric with the axis of the head.

30 The passageway 14 leads into an annular channel 17 which is substantially covered by an annular collar 18. One or more portions of the collar 18 are cut away to provide one 35 or more weirs 19, the edge or edges of which lie on the circumference of a circle concentric with the axis of the head and of the same diameter as the circle on the circumference of which lie the edges of the weir or weirs 16.

40 The depth of the crests over the weirs 16 and 19 depends on the distance of the surface of the liquid in the bowl from the axis of the bowl and, as the edges of the weirs 16 and 19 are equally distant from the axis of the bowl, 45 the depth of both crests will be substantially the same at any given capacity or speed of the machine. The ratio of the discharges is therefore dependent upon the ratio of the width of the weirs 16 and 19.

50 Although in Fig. 1 means are not disclosed for rotating the bowl 10 and receiving the discharges from the outlets 13 and 14, it is to be understood that it is contemplated to mount the bowl 10 in a machine substantially 55 similar to that shown in Fig. 5 in which means are provided for rotating the bowl, and feeding liquid into the bottom of the bowl and discharge compartments are provided for receiving the liquid discharged 60 through the outlets 13 and 14.

Assume that the bowl 10 is being rotated and an emulsion or suspension is being fed into the lower portion thereof. As the emulsion or suspension passes along the bowl, the emulsion or suspension is gradually concen-

trated either near the axis or the periphery of the bowl depending upon the character of the emulsion or suspension. Assuming that the concentrated emulsion is lighter than the continuous phase, the concentrated emulsion will 70 pass over the weir or weirs 16 and discharge through the passageway 13 and the pure continuous phase will pass between the edge of the disk 15 and the inner face of the bowl 10 through the passageway 14 and thence to the 75 annular channel 17 from whence it discharges over the weir or weirs 19. The ratio of the discharges through these passageways is dependent upon the relative widths of the weirs and will remain constant at different capacities and speeds. The widths of the weirs 16 and 19 are so chosen that the desired concentration of emulsion is obtained. In the drawings the weir 16 is disclosed as being narrower than the weir 19 but might be of the 80 same or greater width depending upon the character of the emulsion or suspension being treated. When it is desired to change the concentration of the emulsion another collar 18 having weirs of different widths may 85 be substituted or a different disk 15 having weirs of different widths may be utilized. Preferably a change of concentration is obtained by replacing the collar 18 as the collar is more accessible than the disk 15. 95

Reference to Fig. 4 will make clear the principle of the invention. The tank 10^a corresponds to the bowl 10 into which the suspension is introduced through the pipe 12^a. Liquid may escape over a weir 16^a or 100 through a passageway 14^a and over a weir 19^a. The weirs 16^a and 19^a correspond to the weirs 16 and 19 of the centrifugal machine and are of equal height but may be of different widths, the weir 19^a being shown as having means for varying its width. The passageway 14^a corresponds to the discharge passage 14 of the centrifugal machine. The analogy of the operation of the machine disclosed in Figs. 1 to 3 is as follows. Assume 110 that an emulsion or suspension is supplied to the tank 10^a through the pipe 12^a and that the emulsion concentrates on the upper surface. The concentrated emulsion flows over the weir 16^a and the pure continuous phase flows 115 through the channel 14^a and over the weir 19^a. The level of the discharge crests over the weirs 16^a and 19^a is substantially the same. Since the weirs are of equal height the ratio of the discharges over the weirs is therefore 120 dependent upon the ratio of their widths. With any given ratio of the widths of the weirs the emulsion discharged over the weir 16^a will be of a definite concentration irrespective of the level of the liquid in the tank 125 10^a. If it is desired to vary this concentration, the width of the weir 19^a may be varied and when varied the concentration of the emulsion discharged over the weir 16^a will remain uniform thereafter in spite of wide 130

variations in the speed of rotation of the bowl and in the rate at which the substance to be treated is supplied thereto.

Referring now to Figs. 5, 6 and 7, reference numeral 20 designates a standard supporting a casing 21, and being provided with a bracket 22 overhanging the casing. A bearing 23 is supported by the bracket 22, and has mounted therein a spindle 24 passing through a sleeve 25 and which may be driven by any suitable means such, for example, as a worm 26 and worm wheel 27. A centrifugal vessel or bowl 28 is supportingly coupled to the spindle 24 through the medium 10 of a member which also constitutes the head 29 of the bowl 28. In the head 29 is provided a plurality of skim milk discharge channels 30 leading from the bowl 28 at points near its periphery to an annular 15 groove or port 31 which is partially closed by an annular member 32, which constitutes a weir for the skim milk discharge. A cream discharge duct is provided in the member 29 and consists of a slot 33, the bottom of 20 which extends parallel to the axis of the bowl 28 and is spaced therefrom a distance equal to the radial distance of the inner edge of the annular weir 32. A cup-shaped member 34 is carried by the head 29 and projects into 25 the bowl 28, it being so arranged as to provide a narrow annular passageway between the periphery of the end projecting into the bowl and the interior of the bowl 30, said passageway affording communication between the interior of the bowl and the channels 30.

The lower end of the bowl 28 is steadied by means of an arrangement 36 commonly known as a drag assembly. The whole milk 40 to be separated is conducted through a suitable pipe 37 from a source of supply not shown and is introduced into the bowl through a nozzle 37^a. Cover compartments 38 and 39 are provided around the top of the bowl 28 in position to receive milk and cream discharged through the ducts 30 and 33.

According to this arrangement, the skim milk discharge is controlled by a weir, the edge of which lies on the circumference of a 50 circle, the center of which is coincident with the axis of the bowl. The cream discharge is likewise controlled by a weir, the edge of which, for all practical purposes, lies on the circumference of a circle the center of which is coincident with the axis of the bowl and which is of the same radius as the circle on the circumference of which the edge of the skim milk weir lies. With this arrangement the ratio of the cream discharge to the skim 55 milk discharge is uniform at different capacities and speeds of the device. The thickness of the discharge crests is dependent upon the radial distance of the surface of the liquid from the axis of the bowl and as the 60 weirs are at equal radial distance from the

axis, the thickness of the crest over each is substantially the same. The ratio of the cream discharge to the skim milk discharge depends therefore upon the ratio of the width of the weirs. A change in the radial distance 70 of the surface of the liquid from the axis of the bowl either because of a change in capacity or a change in speed produces proportional variations in the thickness of the cream discharge crest and the thickness of the skim 75 milk discharge crest but the ratio of the two discharges remains uniform so that the percentage of butter fat in the cream remains constant at different capacities and speeds.

The percentage of butter fat in the cream 80 is dependent upon the ratio of the cream discharge to the skim milk discharge which in turn is dependent upon the ratio of the widths of the weirs controlling the discharges. The effective width of the cream slot or weir is 85 variable by means of a screw 40 which is movable into and out of the duct in a transverse direction. As is clearly shown in Fig. 7, longitudinal movement of the screw 40 varies the width of the slot 33. This same effect is 90 also obtainable in the modification disclosed in Figs. 8 and 9. Here a screw 41 is provided in the bottom of the slot and its inner end is cut away so that, in the position shown in Fig. 9, the portion 41^a of the screw lies 95 wholly within a socket at the side of the cream slot. Rotation of the screw, however, brings the edge of the portion 41^a into the cream slot, thereby varying the effective width of the slot. By means of either type 100 of screw, the ratio between the width of the cream discharge weir and the skim milk discharge weir may be varied. As the edges of the weirs controlling these discharges are equally distant from the axis of the bowl, 105 variation in the width of the cream discharge weir effects a variation in the ratio of the cream discharge to the skim milk discharge. A variation in the level of the whole milk in the bowl 30 produces a proportionate variation in both the cream and skim milk discharges, but does not affect the ratio of the 110 cream discharge to the skim milk discharge.

Although the annular member 32 has been disclosed as having its entire inner edge constituting a weir for controlling the skim milk discharge it is evident that there may be substituted a wider annular member provided with one or more cut-away portions having their edges at the same distance from the axis 115 as the bottom of the cream slot, thereby providing one or more weirs for controlling the skim milk discharge. Variation in the ratio of the cream and skim milk discharges may be accomplished by utilizing annular members 32 provided with weirs of different effective widths as well as by varying the width of the cream slot by the cream slot screw.

Theoretically, to keep uniform the ratio 120 between the cream and skim milk discharges, 125 130

the weir controlling the cream slot should be of the same curvature as that of the annular dam for the skim milk discharge. Very satisfactory results are obtainable, however, with 5 a cream slot of rectangular cross-section. The cream discharge is but a small fraction of the skim milk discharge and consequently the cream slot is very narrow. Thus, the cream discharge weir need not be curved but 10 will give very satisfactory results although straight. It is, of course, within the spirit of the invention to make the cream weir of the same curvature as that of the skim milk weir, if absolute uniformity is desired. For all 15 practical purposes, it is not necessary to have the weirs of equal curvature.

It is, of course, understood that various structural modifications may be made without departing in any way from the spirit of 20 the invention as set forth in the appended claims.

In this connection it is pointed out that an important feature is that the weirs over which the constituents into which the substance fed 25 to the bowl is centrifugally separated, must be located at such relative distance from the axis of the bowl that some of each constituent will be discharging over its weir at substantially all rates of feed of the substance to the 30 bowl. When cream is being separated from milk, a cream weir located radially inward of the milk weir would necessitate the building up of a layer of cream above the surface of the skim milk that is discharging over its 35 weir. This would cause the cream globules to coalesce into continuous butter fat unless milk is supplied to the bowl at such a rate that the crest over the milk weir is at least as near the axis of the rotor as the cream weir.

40 But, if the cream and milk weirs are at the same distance from the axis of the bowl there is a concentrating of the emulsion, and milk and cream will both discharge over their respective weirs regardless of the rate at which 45 milk is fed to the bowl, the proportion of cream and skim milk being determined by the relative widths of the weirs. In separating substances of such character that the lighter substance may, without undesirable 50 alteration of it, be discharged over a weir that is radially inward of the other weir, the weirs may be placed at different distances from the axis of the bowl and the relative depths of the crests over the two weirs may 55 be maintained uniform, in accordance with the principles of this invention, at different rates of feeding and different speeds of rotation so long as the relative distance of the weirs from the axis is such that, having due 60 regard for the relative specific gravities of the separated constituents, some of each constituent will be discharging over its weir at substantially all rates of feed to the bowl. In the practice of this invention the weirs employed are not to be confused with mere ori-

fices of which the dimensions may be varied. Such orifices act merely as valves and the volume of flow through them varies greatly with variations in speed of rotation and their position with respect to the surface of the 70 liquid within the bowl.

References in the claims to the maintaining of various conditions at any or all capacities or rates of feed or speeds of rotation, or irrespective of speed or capacity, are, of course, 75 intended to refer only to operative conditions, i. e., conditions under which the desired separation will occur. In general, such conditions are that the speed of rotation will be great enough to keep the liquid in place in the bowl 80 substantially in the form of a hollow cylinder, and to effect the desired separation; and that the capacity or rate of supply to the bowl will be low enough to avoid causing discharge from the supply opening as well as from the 85 discharge openings and to avoid clogging of discharge openings and to ensure that the substance will be in the bowl long enough to be separated. Thus, in the practice of my invention 90 emulsions may be concentrated and mixtures may be divided into predetermined fractions by having weirs that are of properly selected circumferential length and are located either at the same distance or at different distances from the axis of the centrifugal 95 bowl. In all instances the lengths of the weirs will be such as to maintain substantially uniform the relative depths of the crests over them in spite of variations in the rate of supply of material to the bowl and the rate of rotation of the bowl. When cream is being separated from full milk any arrangement of weirs, or rates of supply, or speeds of rotation, that cause the formation of a layer of cream 100 free of milk, will reduce the cream to continuous butter fat; and therefore in the separation of milk and of other substances of such character that a product separated therefrom by centrifugal force is undesirably altered when a layer of that product is subjected to centrifugal force, the discharge of some of each product over its weir at all speeds and all rates of supply is best attained by having the weirs at equal distances from the axis of the bowl. 105 But, when the substance that is being separated is of such character that the separated products thereof may be formed into layers or strata in the bowl without undesirable change, such as undesirable coalescence of dispersed particles, then there is a liquid balance of products within the bowl on opposite sides of the disk 15 and the weirs may be at different distances from the axis of the rotor when so positioned that some of each substance will discharge over its proper weir at 110 all rates of supply and rates of rotation.

115 What I claim as new and desire to secure by Letters Patent is:

120 1. A machine for concentrating emulsion comprising a centrifugal bowl, means for sep- 130

- arately discharging concentrated emulsion and pure continuous phase and means for maintaining constant the ratio of said discharges at any speed or capacity of the machine. 5

2. A machine for concentrating emulsions comprising a centrifugal bowl, means for discharging concentrated emulsion and pure continuous phase from said bowl from points at different radial distances from the axis of the bowl and means for maintaining constant the ratio of the discharges irrespective of the capacity and speed of the machine. 10

3. A machine for concentrating emulsions comprising a centrifugal bowl having discharge passageways leading from points at different radial distances from the axis of the bowl and weirs controlling the discharge from said passageways, said weirs having their edges equally distant from the axis of the bowl. 15

4. A machine for concentrating emulsions comprising a centrifugal bowl having discharge passageways leading from points at different radial distances from the axis of the bowl and weirs of different widths controlling the discharge from said passageways, said weirs having their edges equally distant from the axis of the bowl. 20

5. A machine for concentrating emulsions comprising a centrifugal bowl having discharge passageways leading from points at different radial distances from the axis of the bowl and weirs of variable widths controlling the discharges from said passageways, said weirs having their edges equally distant from the axis of the bowl. 25

6. A machine for concentrating emulsions comprising a centrifugal bowl having discharge passageways leading from points at different radial distances from the axis of the bowl and weirs controlling the discharges from said passageways, one of said weirs being of variable width and all the weirs having their edges equally distant from the axis of the bowl. 30

7. A machine for concentrating emulsions comprising a centrifugal bowl having passageways leading from points at different radial distances from the axis of the bowl, annular members controlling the flow through each of said passageways, each of said annular members having a portion cut away to provide arcuate weirs of equal curvature, the centers of which are coincident with the axis of the bowl. 35

8. A machine for concentrating emulsions comprising a centrifugal bowl having discharge passageways leading from points at different radial distances from the axis of the bowl and an annular member surrounding one end of each discharge passageway, each of said annular members having a portion cut away to provide arcuate weirs of equal curvature, the centers of which are coincident with the axis of the bowl. 40

9. A machine for concentrating emulsions comprising a centrifugal bowl having passageways leading from points at different radial distances from the axis of the bowl, an annular channel communicating with one end of one of said discharge passageways, an annular member substantially closing said annular channel, an annular disk surrounding the opposite end of the other of said passageways, said annular member and disk having portions cut away to provide arcuate weirs of equal curvature, the centers of which are coincident with the axis of the bowl. 45

10. A machine for concentrating emulsions comprising a centrifugal bowl having a passageway leading from a point near the axis of the bowl and a passageway leading from a point near the periphery of the bowl, an annular channel communicating with the outer end of the passageway leading from a point near the periphery of the bowl, an annular member substantially closing said channel, and an annular disk projecting into the bowl and enclosing the inner end of the passageway leading from a point near the axis of the bowl, said annular members being cut away to provide arcuate weirs of equal curvature whose centers are coincident with the axis of the bowl. 50

11. A machine for concentrating emulsions comprising a bowl having passageways leading from points at different radial distances from the axis of the bowl, an annular member controlling the flow from one of said passageways and an annular member controlling the flow to the other passageway, said annular members having portions cut away to form arcuate weirs of equal curvature whose centers are coincident with the axis of the bowl, said annular members being removably connected whereby the relative circumferential extent of said weirs may be varied. 55

12. In a device of the character described a centrifugal bowl having discharge passageways leading from points at different radial distances from the axis of the bowl, weirs controlling the discharge from said passageways, the edges of said weirs being equally distant from the axis of the bowl and means for varying the width of one of said weirs. 60

13. In a device of the character described, a centrifugal bowl having discharge passageways leading from points at different radial distances from the axis of the bowl, weirs controlling the discharge from said passageways and means for maintaining uniform the ratio of the discharges through said passageways at all capacities of the machine. 65

14. In a cream separator, a rotatable bowl having cream and skim milk discharge outlets controlled by weirs equally distant from the axis of the bowl and means for varying the ratio of the discharges through said outlets. 70

15. In a device of the character described a centrifugal bowl having discharge passageways leading from points at different radial distances from the axis of the bowl, an annular member substantially closing said annular channel, an annular disk surrounding the opposite end of the other of said passageways, said annular member and disk having portions cut away to provide arcuate weirs of equal curvature, the centers of which are coincident with the axis of the bowl. 75

16. In a device of the character described a centrifugal bowl having a passageway leading from a point near the axis of the bowl and a passageway leading from a point near the periphery of the bowl, an annular channel communicating with the outer end of the passageway leading from a point near the periphery of the bowl, an annular member substantially closing said channel, and an annular disk projecting into the bowl and enclosing the inner end of the passageway leading from a point near the axis of the bowl, said annular members being cut away to provide arcuate weirs of equal curvature whose centers are coincident with the axis of the bowl. 80

17. In a device of the character described a bowl having passageways leading from points at different radial distances from the axis of the bowl, an annular member controlling the flow from one of said passageways and an annular member controlling the flow to the other passageway, said annular members having portions cut away to form arcuate weirs of equal curvature whose centers are coincident with the axis of the bowl, said annular members being removably connected whereby the relative circumferential extent of said weirs may be varied. 85

18. In a device of the character described a centrifugal bowl having discharge passageways leading from points at different radial distances from the axis of the bowl, weirs controlling the discharge from said passageways, the edges of said weirs being equally distant from the axis of the bowl and means for varying the width of one of said weirs. 90

19. In a device of the character described, a centrifugal bowl having discharge passageways leading from points at different radial distances from the axis of the bowl, weirs controlling the discharge from said passageways and means for maintaining uniform the ratio of the discharges through said passageways at all capacities of the machine. 95

20. In a device of the character described a centrifugal bowl having a passageway leading from a point near the axis of the bowl and a passageway leading from a point near the periphery of the bowl, an annular channel communicating with the outer end of the passageway leading from a point near the periphery of the bowl, an annular member substantially closing said channel, and an annular disk projecting into the bowl and enclosing the inner end of the passageway leading from a point near the axis of the bowl, said annular members being cut away to provide arcuate weirs of equal curvature whose centers are coincident with the axis of the bowl. 100

21. In a device of the character described a bowl having passageways leading from points at different radial distances from the axis of the bowl, an annular member controlling the flow from one of said passageways and an annular member controlling the flow to the other passageway, said annular members having portions cut away to form arcuate weirs of equal curvature whose centers are coincident with the axis of the bowl, said annular members being removably connected whereby the relative circumferential extent of said weirs may be varied. 105

22. In a device of the character described a centrifugal bowl having discharge passageways leading from points at different radial distances from the axis of the bowl, weirs controlling the discharge from said passageways, the edges of said weirs being equally distant from the axis of the bowl and means for varying the width of one of said weirs. 110

23. In a device of the character described, a centrifugal bowl having discharge passageways leading from points at different radial distances from the axis of the bowl, weirs controlling the discharge from said passageways and means for maintaining uniform the ratio of the discharges through said passageways at all capacities of the machine. 115

24. In a cream separator, a rotatable bowl having cream and skim milk discharge outlets controlled by weirs equally distant from the axis of the bowl and means for varying the ratio of the discharges through said outlets. 120

25. In a device of the character described a centrifugal bowl having a passageway leading from a point near the axis of the bowl and a passageway leading from a point near the periphery of the bowl, an annular channel communicating with the outer end of the passageway leading from a point near the periphery of the bowl, an annular member substantially closing said channel, and an annular disk projecting into the bowl and enclosing the inner end of the passageway leading from a point near the axis of the bowl, said annular members being cut away to provide arcuate weirs of equal curvature whose centers are coincident with the axis of the bowl. 125

the effective width of the weir controlling said cream discharge outlet.

15. In a cream separator, a rotatable bowl having cream and skim milk discharge outlets controlled by weirs equally distant from the axis of the bowl and a screw movable in said cream outlet to vary the effective width of the weir controlling said outlet.

16. In a cream separator, a rotatable bowl 10 having cream and skim milk outlets controlled by weirs equally distant from the axis of the bowl and a screw having a portion adapted to move into and out of said cream outlet to vary the effective width of the weir 15 controlling said cream outlet.

17. In a cream separator, a rotatable bowl having cream and skim milk outlets controlled by weirs equally distant from the axis of the bowl and a screw arranged to traverse the cream outlet whereby the effective width of the weir controlling said cream outlet may be varied.

18. In a cream separator, a rotatable bowl having a skim milk outlet and a cream slot 25 at equal distances from the bowl axis, and means to vary the effective width of said cream slot in a circumferential direction.

19. In a cream separator, a rotatable bowl having a skim milk outlet and a cream slot 30 at equal distances from the bowl axis, and means to vary the cross sectional area of said cream slot while maintaining an edge of said cream slot at a fixed distance from the axis of the bowl.

35 20. In a cream separator, a rotatable bowl having skim milk and cream outlets at different radial distances from the axis thereof, weirs controlling said outlets and located at substantially equal distances from the bowl 40 axis, a cylindrical member projecting into the bowl between said cream and skim milk outlets and means for varying the effective width of one of said weirs.

21. In a cream separator, a rotatable bowl 45 having skim milk and cream outlets at different radial distances from the axis thereof, weirs controlling said outlets and located at substantially equal distances from the bowl axis, a cylindrical member projecting into the bowl between said cream and skim milk 50 outlets and means for varying the effective width of the weir controlling said cream outlet.

22. In a cream separator, a rotatable bowl 55 having a cream slot and a skim milk outlet terminating in an annular channel, an annular member overlying said annular channel to constitute a weir for controlling the discharge through said skim milk outlet and 60 located at substantially the same distance from the bowl axis as the edge of said cream slot and means for varying the effective width of said cream slot in a circumferential direction.

65 23. In a cream separator, a rotatable bowl

having a cream slot and a skim milk outlet terminating in an annular channel, an annular member overlying said annular channel to constitute a weir for controlling the discharge through said skim milk outlet, the 70 bottom of said cream slot and the inner edge of said annular member being at the same radial distance from the axis of the bowl and means for varying the width of said cream slot.

75 24. In a centrifugal machine, a bowl having outlets at different radial distances from the axis of the bowl and means for maintaining constant the ratio of the discharge through said outlets irrespective of the distance of the surface of the liquid in the bowl from the axis of the bowl.

80 25. A device of the character described comprising a centrifugal bowl having outlets for separately discharging from said bowl liquids arranged in the bowl by centrifugal force, and means for maintaining constant the ratio of the discharge through said outlets irrespective of the distance of the surface of the liquid in the bowl from the 85 axis of the bowl.

90 26. In a centrifugal machine, a centrifugal bowl, and means for separately discharging therefrom products of centrifugal treatment in substantially constant ratio at varying rates of discharge substantially independently of the proportion in which the products discharged exist in the substance introduced into the bowl.

95 27. In a centrifugal machine, a centrifugal bowl, and means for separately discharging therefrom products of centrifugal treatment in substantially constant ratio at varying speeds of rotation of the bowl.

100 28. In a centrifugal machine, a centrifugal bowl having discharge passageways leading from points within the bowl that are at different radial distances from the axis of the bowl, weirs controlling the discharge from said passageways and located at such 110 relative distance from the axis of the bowl that some of each constituent of the substance fed to the bowl will discharge over its weir at substantially all rates of feed of the substance to the bowl, and means for varying 115 the circumferential extent of one of said weirs.

120 29. In a device of the character described, a centrifugal bowl having discharge passageways leading from points at different radial distances from the axis of the bowl, weirs controlling the discharge from said passageways and means for varying the volume of the discharge through one passageway without varying the crest of the liquid discharging over the weir thereof.

125 30. In a centrifugal machine, a centrifugal bowl having discharge passageways leading from points within the bowl that are at different radial distances from the axis of the 130

bowl, and weirs controlling the discharge from said passageways and being located at such relative distances from the axis of the bowl that some of each constituent of the substance fed to the bowl will discharge over its weir at substantially all rates of feed of the substance to the bowl and said weirs having relative circumferential lengths such that the radial depth of liquid flowing over one

of said weirs is equal to the radial depth of liquid flowing over the other of said weirs at substantially all rates of feed to the bowl of a substance of substantially uniform composition.

In testimony whereof, I have signed my name to this specification.

LEO D. JONES.
